UNITED STATES PATENT OFFICE.

JOHN S. S. FULTON, OF CHICAGO, ILLINOIS, ASSIGNOR TO UNITED CONVEYOR CORPORATION, OF CHICAGO, ILLINOIS, A CORPORATION OF ILLINOIS.

CONVEYER FITTING.

Application filed October 31, 1921. Serial No. 511,887.

To all whom it may concern:

Be it known that I, JOHN S. S. FULTON, a citizen of the United States, residing at Chicago, in the county of Cook and State of Illinois, have invented certain new and useful Improvements in Conveyer Fittings, of which the following is a description.

My invention relates to improvements in conveyer fittings, and more particularly it relates to such a pipe fitting used in connection with conveyers for ash or other similar material. One of the objects of my invention is to provide a fitting for such a conveyer in which the entering ash will impact or impinge on a flat surface provided in the fitting and thus eliminate grinding of the interior surface of the fitting by the ash impacting thereon. In the conveyer fittings, as heretofore constructed, the back-
ing part of the fitting, that is, the part receiving the impact of the entering ash or other material thereon due to its change of direction, is generally arcuate in cross-section so that the ash impacting therewith will be spread or directed over said arcuate surface in arcuate paths, while in my improved fitting, the ash impacts against a surface perpendicular or at an angle to the direction of travel of the ash and changes its direction of travel, with a minimum of scouring action on the back of the fitting, it being understood that the entering ash is conducted through the pipe section by a suction or a jet of steam, air, or the like. Another object of my invention is to provide a sectional pipe fitting for a conveyer as above described in which the wearing part or wear back may be easily renewed without disassembling or removing any other part of the fitting. Another object of my invention is to provide an improved form of packing joint for a fitting as above described and improved means for drawing and securing the parts together. Among other objects of my invention I have sought to provide a device as above described which shall be economical, efficient, convenient, durable, and satisfactory for use wherever found applicable. Many other objects and advantages of the construction herein shown and described will be obvious to those skilled in the art from the disclosure herein given.

To this end my invention consists in the novel construction, arrangement and combi-

nation of parts herein shown and described, and more particularly pointed out in the claims.

In the drawings, wherein like reference characters indicate like or corresponding parts;

Figure 1 is a vertical elevation of my ash conveyer system as applied to a series of boiler furnaces, some of the parts being shown in section;

Figure 2 is an end view of one of my improved conveyer fittings;

Figure 3 is a side elevation of the same;

Figure 4 is a sectional view taken substantially on the line 4—4 of Figure 3; with the wear or wear back part removed;

Figure 5 is a section taken substantially on the line 5—5 of Figure 2;

Figure 6 is a section taken substantially on the line 6—6 of Figure 3;

Figure 7 is an enlarged detailed view of my improved form of joint; and

Figure 8 is a sectional view of another form of my conveyer fitting.

In the drawings, wherein I have illustrated a preferred embodiment of my invention, 1 and 2 represent ash intake fittings having an intake communicating with a point adjacent to the ash pit of the boiler furnace and having their discharge ends in communication with the bore of pipe sections 3 of the conveyer section. The elbows 4 are arranged at the top and bottom of the riser pipe of the conveyer system, or other desired points, the entire system emptying into the ash container 5 or the equivalent, wherefrom the ashes may be discharged into any suitable means for removing them. Connected to said elbows 4 are steam or air jets 7, said jets being fed by a main steam or air pipe 6.

Each of the elbow fittings 4 comprises a body part 8 and a renewable wear back part 9 adapted to be removably secured thereto. 10 indicates the intake end of the chamber through the fitting, and 11 indicates the discharge end thereof, there being flanges 12 and 13 at the intake and discharge ends of the fitting whereby said fitting may be connected to adjacent pipe sections, as shown in Figure 2. Bolt holes 14 are provided in one or both of said end flanges through which tightening bolts may be inserted to secure the parts to the adjacent pipe fittings. The parts 8 and 9 are prefer-

ably made of a special hard metal, the renewable wear back being of a harder material than that of the body part if desired. As it would be extremely difficult to provide a pipe tap in a hard metal for the entrance of the steam jet nozzle, I have found it highly desirable in many cases to provide a soft iron plug 15, which is set in place in the mold when the conveyer section is cast, so that it is substantially integrally secured thereto. This feature however is not essential. The nozzle 16 is threaded into said soft iron plug, said nozzle being adapted to be connected to the steam pipe 7.

15 As it is very vital to the successful operation of the conveyer that the large end of the steam jet nozzle is pointed inward, the threads at the inner and outer ends of the nozzle may be of different pitch, so that the 20 nozzle may be placed in position on the fitting only in the correct manner. I, therefore, generally provide different threads for this purpose.

The wear back 9 has a flat inner surface 25 17 opposite the intake 10, said surface in the type of fitting shown lying substantially in a plane perpendicular to the direction of travel of the incoming ash, as indicated by the arrows in Figure 5, so that as the 30 ash impinges or impacts on the flat surface 17 it will rebound and change its direction of travel and be carried through the discharge end 11 by the steam jet coming through the nozzle 16. Thus on account of 35 the flat impact surface of the wear back the grinding or scouring action of the ash on the wear back is reduced to a minimum. It will be noticed that the flattened part of the wear back is also thickened in cross-section 40 so that the longevity of said part is greatly increased, the remaining portion of said wear back gradually decreasing in cross-section to the discharge end.

The meeting edges 18-19 of the body 45 part and wear back part respectively, are preferably flanged as at 20-21, and in each of these edges is formed a series of stepped portions or shoulders, a packing material 22 being adapted to be inserted between said 50 opposed edges when the two parts are assembled. I have found a mixture of cement and asbestos highly satisfactory for such a packing material. As shown in Figure 7, the edge 18 of the body part 8 has two 55 shoulders 23 and 24 lying in planes parallel to and spaced apart transversely of the fitting, there being parallel walls 25, 26, and 27 spaced apart and forming the bounding walls of each of said steps or shoulders 23 and 24. The wear back 9 has formed in its edge 19, steps or shoulders 28 and 29 parallel to each other but of a different obliquity than the steps 23, 24, and lying in planes spaced apart transversely of said 65 wear back, said planes being bounded by

walls 30 and 31 corresponding to the walls 25 and 26 of the body member 8. When the parts are assembled the walls of the steps 23-28 and 24-29 respectively form outwardly converging pockets or grooves 70 32 and 33 respectively, said pockets extending the entire perimeter of the meeting edges 18 and 19, whereby when said parts 8 and 9 are secured together in place the packing is pressed tightly in said grooves and can 75 not be blown out, nor sucked out, as the outer ends of said pockets are smaller in cross-section than the inner ends.

Near one end of the fitting, the flanges 18 and 19 have aligned lugs 34 and 35 80 formed thereon and projecting outwardly therefrom, said lugs having apertures or bores 36 therethrough, the aligned axes of said apertures being perpendicular to the plane of juncture of said parts 8 and 9. Near the other end of the parts 8 and 9 I have provided outwardly extending apertured lugs 37 and 38, one on each flange 18 and 19 respectively, the aligned axes of 85 said apertures extending obliquely to the plane of juncture of the parts 8 and 9. Through the aligned lugs 37 and 38 are positioned attaching bolts or screws 40 and through the other aligned lugs are positioned 90 attaching screws or bolts 41, whereby the parts 8 and 9 may be tightly secured together. In practice, the bolts 41 are first tightened up and then the bolts 40 are tightened, thus moving the parts 8 and 9 past one another in opposite directions 95 along their line of juncture, and spreading the sealing or packing material firmly into place and also tending to move the flange 13 of the part 9 into close engagement with the adjacent flange of the adjacent pipe 100 section.

Whenever it is desired to inspect the fitting which is not essential it is not necessary in the construction illustrated that all the parts be disconnected or disassembled, and whenever it is desired that a new wear back be put in place, the bolts 40 and 41 may be disconnected and the old wear back 9 removed and a new one applied to the part 8, whereupon the bolts 41 and flange bolts are 110 first partially tightened up and the subsequent tightening up of the bolts 40 will move the flange 13 of the wear back into close engagement with the cooperating flange of the adjacent part. The remaining bolts are then tightened up.

Figure 8 represents a modified form of pipe fitting wherein the change of direction of travel of the ash from inlet to discharge is 45 degrees instead of 90 degrees as in the first form. In this modification the body member is indicated at 42 and the wear back at 43, the wearing surface 44 of the wear back being flat and lying in a plane at an 125 angle, as shown, substantially perpendicular 130

lar to the direction of the movement of the incoming ash, as indicated by the arrow in Figure 8. The steam jet is secured to the body part at 45 and directed through the outlet end 46 of the fitting, the inlet end of said fitting being designated as 47. The meeting flanges of the body part and wear back are indicated as 48 and 49 respectively, there being aligned lugs 50 projecting outwardly therefrom and secured together by bolts 51 or by any suitable or equivalent means. The flat or straight inner face of the wear-back tends to prevent wear and swirling of the material, and it will be noticed that the point of impact or stopping of the ash of the material is substantially adjacent to the steam jet, thus eliminating wear above the elbow, which is of great importance. While I have shown a plane 45 degrees and 90 degrees, it will be obvious that the construction herein set forth may be employed with a 22½ plane elbow, or with other styles, including booster fittings and the like. I have not considered it necessary to illustrate all of these styles of fittings as it is believed that the embodiment herein set forth in various styles of fittings will be obvious to those skilled in the art.

Having thus described my invention it is obvious that various immaterial modifications may be made in the same without departing from the spirit of my invention; hence I do not wish to be understood as limiting myself to the exact form, arrangement, construction and combination of parts herein shown and described, or uses mentioned.

What I claim as new and desire to secure by Letters Patent is:

1. A split conveyer of the kind described, comprising a body part and a wear back part, and means for securing said parts together at their plane of juncture, said means comprising a pair of aligned apertured lugs on the meeting edges of said parts, the axes of the apertures being perpendicular to said plane of juncture and a second pair of apertured aligned meeting lugs on the meeting

edges of said parts and spaced from said first named lugs, the axes of the apertures through said last named lugs being oblique to the plane of juncture of the parts, and means through each of said pair of registering lugs for securing said parts together. 50

2. A split conveyer of the kind described, comprising a body part and a wear back part, and means for securing said parts together at their plane of juncture, said means comprising a pair of aligned apertured lugs on the meeting edges of said parts, the axes of the apertures being perpendicular to said plane of juncture, and a second pair of apertures aligned meeting lugs on the meeting edges of said parts and spaced from said first named lugs, the axes of the apertures through said last named lugs being oblique to the plane of juncture of the parts, and means through each of said pair of registering lugs for securing said parts together, and means for discharging a jet of impelling fluid substantially parallel with the face of the wear back and into the passing material. 60

3. A split conveyer fitting of the kind described comprising a body part and a wear part, and means for securing said parts together at their plane of juncture, said means comprising a pair of apertured aligned lugs on each of said parts near one end thereof, the axes of said aligned apertures of the lugs being perpendicular to said plane of juncture, and another pair of lugs on said members at their meeting edges near the opposite end thereof, the axes of the aligned apertures of said last mentioned pair of lugs being oblique to said plane of juncture of the parts, and means adapted to be positioned through each pair of registering lugs to secure said parts together. 70

In testimony whereof, I have hereunto signed my name in the presence of two subscribing witnesses.
